UNITED STATES PATENT OFFICE.

ERNEST O. SEITZ, OF DETROIT, MICHIGAN, ASSIGNOR TO C. M. HALL LAMP COMPANY, OF DETROIT, MICHIGAN, A CORPORATION OF MICHIGAN.

LAMP RING.

Application filed October 8, 1921. Serial No. 506,250.

To all whom it may concern:

Be it known that I, ERNEST O. SEITZ, a citizen of the United States of America, residing at Detroit, in the county of Wayne 5 and State of Michigan, have invented certain new and useful Improvements in Lamp Rings, of which the following is a specification, reference being had therein to the accompanying drawings.

10 The invention relates to rings used for the mounting of the lens of lamps and in connection therewith constituting the removable lamp front or door. Such rings are provided with a portion for bearing against 15 the margin of the lens and also with a flange for engagement with the lamp body and provided with securing means usually locked or unlocked by a rotational movement. The outer surface of the ring is 20 formed with an ornamental finish of enamel or nickel-plated, but the inner surface and locking parts are better protected by zinc, galvanizing or other rust-proofing treatment.

25 It is the object of the present invention to obtain a construction of ring in which the inner portion, including the locking mechanism, is separately formed and is readily attachable to the finished outer portion.

30 This permits of galvanizing or otherwise rust-proofing the inner portion and of ornamental finishing the outer portion in any desired manner while the two parts are detached and of subsequently assembling the 35 two. It also permits of rejection of a defective part without discarding the whole structure. With these objects in view the invention consists in the novel construction as hereinafter set forth.

40 In the drawings:

Figure 1 is a sectional elevation of the ring;

Figure 2 is an elevation partly in section showing the joint portion of the inner ring;

45 Figure 3 is a section through the joint of the inner ring;

Figure 4 is a sectional perspective view of the assembled rings; and

Figure 5 is a sectional side elevation.

50 A is the outer ring formed of pressed sheet metal and of any desired construction, but as shown having the cylindrical peripheral flange B with an inturned rear edge portion C and the radially inwardly extending front portion D. E is the inner

portion of the ring which, when assembled with the outer ring, has a portion F bearing against the inner surface of said outer ring, a portion G parallel to but spaced from said inner ring, a radially extending portion H connecting the portions F and G and a radially inwardly extending portion I which forms a retainer for the gasket which forms the sealing joint with the lens. The ring E is further provided with the lugs J attached thereto which are radially slotted to engage cooperating locking pins on the lamp body.

With the construction of ring E as thus far described, it would be impossible to 70 engage the same with the outer ring after the completion of the latter, for the reason that the inturned flange C on the ring A is of a diameter less than that of the portion F of the ring E. Consequently, it has 75 been the practice in the past to turn in the flange C subsequent to the assembly of the rings A and E, but this necessitates the nickel plating or other finishing of the outer ring after assembly. Also, where there is a 80 defect in the outer finish, the whole structure is rejected, for the inner portion cannot be detached.

To permit of completely finishing the inner and the outer rings while separate 85 from each other and subsequently assembling the same, the inner ring E is split and the portions on opposite sides of the split are so fashioned as to form an interlocking engagement with each other. Preferably 90 a continuous ring is first formed which is subsequently severed and the portions on opposite sides of the severing point are fashioned to form projecting tongues K and K'. These are laterally offset so as 95 to engage each other upon opposite sides and in this manner to hold the two end portions from misalignment. The tongues are formed on the portion G of the ring E and as this portion is spaced from the 100 outer ring A, it may be circumferentially expanded by the use of a suitable tool so as to engage or disengage the tongues K and K' from each other.

With the construction as described, when 105 the rings A and E are to be assembled, the ring E has the end portions thereof overlapped, which permits of contracting the diameter sufficiently to engage the ring in the opening of the flange C. When thus 110

engaged, a tool (not shown) of any suitable construction is used for expanding the inner ring to slightly separate the adjacent ends thereof and to permit the tongues K and K' to engage with each other. When the expanding pressure is released, the resiliency of the ring will cause the ends to engage and the tongues will then hold them from misalignment.

10 As the inner ring is subject to a rotary thrust or torque during the locking or unlocking movement, it is essential that it should be locked to the outer ring. This I accomplish in a simple manner by striking inward from the outer ring a tongue L which engages a notch M in the inner ring. The tongue and notch are preferably located at the bottom of the ring when mounted upon the lamp and the aperture N formed by the 15 striking in of the tongue performs the further function of a drain hole for the escape of condensation.

What I claim as my invention is:

1. In a lamp, an outer ring and an inner 25 split ring extending clear across the inner surface thereof and forming an attachable lining and strengthening rib therefor.

2. In a lamp, an outer ring having in- 30 turned flanges on opposite sides of a central portion and an inner ring forming a lining having a portion bearing against the portion of said outer ring between said flanges, said inner ring being split to permit of first collapsing and then expanding for engagement 35 with said outer ring, and means for locking the portions on opposite sides of the split in alignment.

3. In a lamp, the combination with an outer ring having radially inwardly extend- 40 ing flanges on opposite sides of a central portion, of an inner lining ring having a portion for engaging said central portion of the outer ring, said inner ring being split to permit of first collapsing and then ex- 45 panding into engagement with said outer ring, and interlocking tongues on the portions of said inner ring on opposite sides of the split for holding the same in alignment.

4. In a lamp, an outer ring and an inner

ring in engagement with each other, and 50 means for locking said rings from relative rotation comprising a tongue struck out from one and engaging a notch in the other, the space formed by the striking out of said tongue being located in the bottom portion 55 of the ring and constituting a drainage aperture for the ring.

5. In a lamp, an outer ring and an inner ring in engagement with each other, said inner ring having a flange along one edge 60 adapted to lie flush with said outer ring, means for locking said rings from relative rotation comprising a tongue struck inward from said outer ring in the bottom portion thereof and engaging a notch in said flange, 65 said notch together with the aperture formed by the striking out of said tongue constituting a drainage aperture for the ring.

6. In a lamp, an outer ring comprising a wide flat central portion having inturned flanges at both edges thereof, an inner ring forming a lining and comprising a wide flat central portion adapted to lie parallel with said first mentioned central portion and provided with flanges thereon for holding said 75 central body portion spaced from each other, said inner ring being split to permit of its insertion between the flanges of said outer ring and means for locking the abutting ends of said split ring comprising a pair of 80 tongues formed on each end adapted to engage each other on opposite sides of the split.

7. In a lamp, an outer ring and an inner ring in engagement with each other, and means for locking said rings from relative 85 rotation comprising a plurality of indentations upon one of said rings and surfaces upon the other ring corresponding to the contour of said indentations and adapted to snugly fit therein and a tongue struck up 90 from the lower edge of the outer ring engaging a notch in the other, the space formed by the striking out of said tongue being located in the bottom portion of the ring and constituting a drainage aperture therefor. 95

In testimony whereof I affix my signature.

ERNEST O. SEITZ.
